UNITED STATES PATENT OFFICE.

IRA JAMES KAAR, OF HAVELOCK, NEBRASKA.

DOUBLE LISTER.

SPECIFICATION forming part of Letters Patent No. 760,872, dated May 24, 1904.

Application filed August 24, 1903. Serial No. 170,562. (No model.)

To all whom it may concern:

Be it known that I, IRA JAMES KAAR, a resident of Hayelock, in the county of Lancaster and State of Nebraska, have invented certain new and useful Improvements in Double Listers; and I do hereby declare the following to be a full, clear, and exact description of the invention, such as will enable others skilled in the art to which it appertains to make and use the same.

My invention relates to an improved double lyster, and more particularly to an improved two-row loose-ground lyster, the object of the invention being to provide improvements of this character which will be of comparatively simple construction, which will be at all times under the control of the operator, and which can be easily, quickly, and accurately adjusted at all times.

A further object is to provide improved mounting for the furrow-opening disks and improved cleaning mechanism therefor.

With these objects in view the invention consists in certain novel features of construction and combinations and arrangements of parts, as will be more fully hereinafter described, and pointed out in the claims.

In the accompanying drawings, Figure 1 is a top plan view illustrating my improvements, parts being broken away. Fig. 2 is a side view, and Fig. 3 is a diagrammatic plan view, illustrating the disk-cleaners. Figs. 4 and 5 are views illustrating the clutch-operating devices.

1 represents a U-shape channel-iron frame provided with alined bearings for the axle 2, on which are mounted the concave rimmed traction-wheels 3. A shaft 4 is supported in bearings at the rear of frame 1 and has scrapers 5 secured thereto and adapted to clean the wheels 2 when moved into engagement therewith by a treadle 6, pivoted to frame 1 and connected by a rod 7 with a crank-arm 8 on shaft 4, as will be readily understood.

A shaft 9 is secured in lugs 10 on frame 1 slightly in advance of axle 2, and a hollow tubular casting 11 is mounted on said shaft and has forwardly-projecting arms 12 connected by bolts or rods 13 with longitudinally-located adjusting-bars 14, coiled springs 15

being suitably mounted on bolts or rods 13 to give to the connection the desired flexibility or elasticity. On casting 11 an upwardly and rearwardly extending spring seat-bar 16 is loosely mounted, and its free end, to which the operator's seat 17 is secured, is braced by an upright 16^a, secured to the frame. An operating-lever 18 is secured at one end to one end of the casting 11 and has a spring-pressed detent 19 to lock the lever to a toothed segment 20 on frame 1 and secure the casting 11 and adjusting-bars 14 at any adjustment. To assist the lever 18, I secure a bent bar 21 between its ends to casting 11 and provide foot-rests 22 at the ends of this bar in advance of and behind the casting, so that the operator can by foot-pressure on these foot-rests assist his arms in the adjustment of the machine.

The forward ends of frame 1 are connected by hinges 23 with brackets 24, and the latter are secured to parallel channel-irons 24, extending from side to side of the machine and supported by rod-frames 24^b on bars 14, and the forward ends of said bars are connected by rods 25 with a cross-bar 26, secured to the tongue 27 and connected therewith by diagonal braces 28, said braces being secured in couplings 29, in which cross-bar 26 is mounted and secured.

Seedboxes 30 are supported above and slightly to the rear of irons 24 upon framework 31, and seed-dropping boots 32 are located below the outlets of said boxes 30 and are adjustably secured thereto by rods 33, said rods having a series of openings 34 therein, in any of which pins 35 may be located to secure the boots at any elevation desired, rearward movement of the lower end of the boots being prevented by metal straps 36 encompassing them and connected by rods 37 with link 90 brackets 38, which latter are pivotally connected to the couplings 29 above referred to, and bars 39 are connected with these couplings and extend rearward across the irons 24 and are bent laterally and form a portion of 95 the base of seedbox-supporting framework 31.

From the irons 24 vertical twisted bars 40 depend and carry at their lower ends bearings 41 for journals supporting rotary concavo-convex furrow-opening disks 42, located at an 100

angle with relation to each other and the boots 32 above referred to, located in a line between and to the rear of said disks. The lower ends of bars 40 are braced against rearward bending by yoke-bars 43, pivotally secured between their ends in a bifurcated portion of bracket-link 38.

A short shaft 44 has rotary mounting at one end in a hinge 23 and at its other end in a bearing on tongue 27. The shaft 44 being thus located coincident with the hinge 23, the maintenance of said shaft equidistant from the axle will be insured regardless of the adjustment of the frame and disks. On this shaft 44 three sprocket-wheels 45 of varying diameters and number of teeth are secured. Any of them may be connected by a sprocket-chain 46 with any of a like graduated series of sprocket-wheels 47 on axle 2, and a sprocket-chain 48 connects one of the wheels 45 with a sprocket-wheel 49 on the seed-dropping shaft 50, extending below the seedboxes and operating any desired seed-dropping mechanism.

The sprocket-wheels 47 on axle 2 are locked to turn together in one series and are locked to axle 2 by a spring-pressed clutch 51, on which latter a lug 52 is located, and a cam-lug 53 is provided on tubular casting 11, so that when said casting is turned in elevating the disks the cam-lug 53 will be moved into the path of lug 52, throw the clutch, and prevent movement of chain 46 when the axle 2 turns, thus permitting the machine to be moved from place to place without operating the seed-dropping mechanism.

Secured across the disk-frame in rear of irons 24 are parallel guide-rods 54, between which four blocks 55 are mounted to slide. These blocks are pivotally connected to the upper ends of levers 56, pivoted between their ends on lugs 57, secured to the disk-bearing supports and carrying at their lower ends scrapers 58 adjacent to the concave working face of the four disks.

A lever 59 is fulcrumed between its ends at the center of guide-rods 54, extends to a horizontal position longitudinally of the machine, and has an upwardly-bent operating-handle 60 at its rear end in proximity to the operator's seat. Link rods 61 connect the forward end of lever 59 with the first and third blocks 55 from the right of the machine, and similar link rods 62 connect the other two blocks 55 with the lever 59 on the opposite side of its fulcrum, so that when the lever is swung in one direction all of the scrapers will be moved to a position to scrape the disks and away from the disks when the lever is swung in the opposite direction. To limit the movement of this lever 59 in both directions, I provide a curved loop 63, secured to the machine-frame and through which the lever is passed and its movement confined or restricted thereby.

The operation of my improvements is as

follows: The disks 42 open a furrow into which the boots 32 direct the seed, over which wheels 3 pass to cover or bury the seed. The rotation of axle 2, through the medium of sprocket-wheels 47, chain 46, sprocket-wheels 45, chain 48, sprocket-wheel 49, and shaft 50, operates the seed-dropping mechanism to control the feed, and the lever 59 can be moved to clean the disks at will. When it is desired to elevate the disks, casting 11 is turned, through the medium of hand-lever 18 and foot-lever 21, to raise bars 14 and the disk-frame, as is readily understood, and this movement of casting 11 moves cam-lug 53 into the path of lug 52 on clutch 51 to disconnect the sprocket-wheels 47 from axle 2 and discontinue the seed-dropping operation.

A great many slight changes might be made in the general form and arrangement of the several parts described without departing from my invention, and hence I would have it understood that I do not restrict myself to the precise details set forth, but consider myself at liberty to make such slight changes and alterations as fairly fall within the spirit and scope of my invention.

Having fully described my invention, what I claim as new, and desire to secure by Letters Patent, is—

1. In a double lister, the combination with a main frame supported on wheels, a disk-frame hinged to the main frame, seed-dropping mechanism including seedboxes on the disk-frame, seed-dropping boots below the seedboxes, upright arms on said boots, each of said arms having a series of perforations, and pins to be passed through any of said perforations and into the seedboxes to secure the boots at any desired elevation.

2. In a double lister, the combination of two pairs of concavo-convex disks located at an angle with relation to each other, parallel guide-rods above the disks, four movable blocks in said guide-rods, four levers pivoted between their ends and connected at their upper ends to said blocks, scrapers on the lower ends of said levers adjacent to the concave working faces of said disks, and means for moving said blocks to simultaneously move the scrapers toward and away from the disks.

3. In a double lister, the combination of two pairs of disks located at an angle with relation to each other, scraper-levers pivoted between their ends and located adjacent to the disks, an operating-lever fulcrumed between its ends, rods connecting the upper ends of alternate scraper-levers with the operating-lever on opposite sides of its fulcrum to simultaneously move the scrapers toward or away from the disks.

4. In a double lister, the combination of two pairs of disks located at an angle with relation to each other, scraper-levers pivoted between their ends and located adjacent to the disks, an operating-lever fulcrumed between

its ends, rods connecting the upper ends of alternate scraper-levers with the operating-lever on opposite sides of its fulcrum to simultaneously move the scrapers toward or away from the disks, and means for limiting the movement of said operating-lever.

5 In testimony whereof I have signed this

specification in the presence of two subscribing witnesses.

IRA JAMES KAAR.
